(57) **CLAIM**

The ornamental design for a pneumatic fastener driving tool
body, as shown and described.

DESCRIPTION

FIG. 1 is a perspective view of a pneumatic fastener driving
tool body showing our new design;

FIG. 2 is an end elevation view thereof from the left of FIG.
1;

FIG. 3 is an end elevation view thereof from the right of FIG.
1;

FIG. 4 is a top plan view thereof;

FIG. 5 is a side elevation view thereof from the right of FIG.
2;

FIG. 6 is a side elevation view thereof from the left of FIG.
2; and,

FIG. 7 is a bottom plan view thereof.

The driving mechanism, magazine and brace shown in
dashed lines form no part of the design.
